UNITED STATES PATENT OFFICE.

ARTHUR R. EARNSHAW, OF WYNNEWOOD, PENNSYLVANIA.

FLOAT VALVE.

Application filed January 4, 1924. Serial No. 684,329.

To all whom it may concern:

Be it known that I, ARTHUR R. EARNSHAW, a citizen of the United States, residing at Wynnewood, in the county of Montgomery and State of Pennsylvania, have invented certain new and useful Improvements in Float Valves, whereof the following is a specification, reference being had to the accompanying drawings.

10 This invention relates to float valves, and it has more particular reference to that type commonly designated as automatic, the primary object being to provide a valve that is uninfluenced by pressure variations at all 15 times.

Another object of my invention is to provide a float valve embodying adjustable means whereby frictional retardation is reduced to a minimum or substantially eliminated.

20 A further object is the provision of a float valve for use more especially in refrigerating apparatus, the same functioning as a check between the compressor and cooling 25 unit to permit the building of pressure for condensation of the gaseous refrigerant; to permit said refrigerant as fast as it is liquefied under pressure to automatically flow into the cooling coil; to prevent the entry 30 into the latter of any of the gaseous refrigerant; and to purge out any foreign gas that may be in the system.

With the foregoing and other objects in view, this invention consists in the novel 35 float valve, one practical embodiment whereof is hereinafter fully described, illustrated by the accompanying sheet of drawings, and more particularly defined by the subjoined claims.

40 In the drawings, wherein like characters of reference designate the same or corresponding parts in all the views:—

Fig. I, is a view in elevation of my novel float valve with parts broken away and in 45 section to better disclose certain underlying features.

Fig. II is a part sectional plan thereof; and,

Fig. III is a fragmentary detail view of 50 the valve control proper.

According to the form of the invention illustrated, the casing 4 of my novel float valve is substantially fan-shaped in contour, said casing being a unitary structure 55 embracing spaced front and back walls 5,

6 respectively, converging walls 7, 8, and a curved wall 9, the latter having apertured integral bosses 10, 11 for attachments hereinafter alluded to. The aforesaid wall 8, for example, is formed with an outwardly 60 projecting neck 12, conveniently—though not essentially—rectangular in cross-section with a central bore 13, adapted to receive the correspondingly shaped insert portion 14 of a ported block 15. This ported block 15 is formed with a surrounding flange 16 of like configuration to the neck 12, and to which it is secured by means of studs 17 passed through holes 18 in said flange— 65 with interposition of a suitable gasket 19 to 70 ensure an air and fluid tight connection—in the well-known manner.

Centrally, and on the exterior portion of the ported block 15, is an elongated protuberance 20 that is longitudinally bored to 75 provide a cavity 21, the outer end whereof is screw-threaded to accommodate a discharge connection 22.

Integral with or mechanically attached thereto, and diametric to, the aforesaid insert portion 14, is an outstanding lug 23 through which I drill a port 24 longitudinally of the block 15,—as best understood from Fig. I, said port communicating with the cavity 21 for a purpose later on explained, 80 and having its inner end closed by an appropriate plug 25. Through one face of the lug 23 I drill a relatively smaller hole or port 26 that communicates with the longitudinal port 24 just described, and said small 85 port 26 is automatically opened and closed by mechanism now to be described.

Transversely of the lug 23 I drill a hole 27 affording bearing for a pivot pin or stout wire 28 that is bent upon itself at 29 and 90 appropriately shaped to provide an angled portion 30 and attaching terminal 31. This attaching terminal or free end 31, it will be observed, is conveniently twisted into a plane at right angles to the portion 30, and to said 95 free end the float 32 is secured by solder, or otherwise as found most convenient.

The valve member proper consists of a rockable cut-off or shutter 33 apertured at 34 to have a loose fit on the pivot pin 28, 100 and it is also provided with offsets 35 between which one limb of the aforesaid angled portion 30 snugly seats. It is to be particularly noted at this juncture that the abutting faces of the lug 23 and rockable 105

cut-off or shutter 33 are machined and polished to reduce friction and provide a seal. To more effectively minimize such possible friction, the cut-off or shutter 33 is preferably grooved transversely at 36, whereby the actual surface contact between the parts 23, 33 is further reduced, and the sensitiveness of the device increased.

- In order to automatically compensate for wear between the parts 23, 33, as well as to maintain close cooperation therebetween, I screw-thread the free end of the pivot pin 28 to receive a nut or nuts 37 between which and the adjacent face of the lug 23 I interpose a compression spring 38 that functions to retain the cut-off or shutter 33 in close or sealing contact with the machined face of the lug 23, as will be readily understood on examination of Fig. II more particularly.
- 20 An inlet connection 38 is fitted to the apertured boss 11, while a relief cock or valve 39 is fitted to the other boss 10 for manually or automatically purging any foreign gas or releasing any excess that may 25 accumulate in the casing 4.

Assuming that my novel float valve is interposed between the liquor line and condenser of a domestic refrigerating apparatus for example, it will be obvious that said 30 float valve will constitute an automatic and absolute control over the supply of active refrigerant to the evaporator. Obviously the liquefied refrigerant accumulated in the casing 4 will thereupon flow through the 35 port 24, cavity 21 and discharge conduit 22 to the expansion coil. Still further it will be understood that by removing the studs 17, the entire valve mechanism can be withdrawn for cleaning, repair, or adjustment 40 with a minimum expenditure of time and labor.

From the foregoing description it will be clearly apparent that the angular formation of the casing 4 provides a comparatively 45 small housing or chamber just large enough to accommodate the movements of the float 32, thereby obviating the necessity for trapping an excessive quantity of refrigerant in the casing. Furthermore the angular side 7 50 of the casing 4 prevents the float 32 from rising to a position where the center of gravity would be such that it would not fall and close the valve when the liquor level recedes.

55 The cut-off 33 is rockable on the pivot pin 28 so that it may always be held flat to the closure surface without being influenced by any movement or torsion of the float 32.

Still further it will be apparent that by 60 my invention I have devised a simple, cheap and very effective automatic float valve, the same being especially useful for the purposes had in view; and while I have described in detail one practical embodiment and application thereof it is to be understood that the

right is hereby reserved to make such changes and variations in the design as fairly fall within the scope of the appended claims.

Having thus described my invention, I claim:

1. A float valve embodying a casing having a pair of convergent walls with provision for a supply connection, one of said walls being apertured, an insert closure for said aperture having an axial duct affording communication between an outlet cavity and a relatively small port, a cut-off shutter rockable on an extension of the closure and controlling said discharge port, said shutter being transversely grooved whereby frictional resistance to movement is reduced to a minimum, and a float secured to the cut-off pivot pin, said closure, cut-off and float, being removable as a connected unit. 85

2. A float valve embodying a casing having a pair of convergent walls and provision for a supply connection, one of said walls having an apertured neck, a closure for attachment to said neck and affording a discharge outlet, a cut-off pivoted to a projection on said closure, the pivot member consisting of a rod bent upon itself to provide an angled portion with a terminal extension, a float secured to the aforesaid terminal extension, and means whereby frictional resistance to movement of the cut-off is reduced to a minimum. 95

3. A float valve embodying a casing having adjacent convergent walls and provision for a supply connection, one of said walls having an apertured neck, a closure for attachment to said neck and affording a discharge outlet, a cut-off pivoted to a projection on said closure, the pivot pin consisting of a rod bent upon itself to provide an angled portion and terminal extension, said angled portion being engaged by ears on the cut-off, means whereby frictional resistance to movement of the cut-off is reduced to a minimum, and a float secured to the aforesaid terminal extension. 100

4. A removable closure for float valves consisting of a unit having a co-extensive lug, a discharge cavity in said unit, a communicating axial duct and outlet port, a cut-off for the port, a pintle for said cut-off fashioned to provide a pivot pin with an angled portion and terminal extension, a float secured to the terminal extension, offsets on the cut-off engaging the angled portion of the pivot pin, and an adjustable spring for automatically maintaining the cut-off in engagement with the aforesaid lug. 115

5. As an article of manufacture a closure unit for valves having a co-extensive lug, an axial duct in said unit connecting a cavity with a discharge port, a cut-off for 120

the port engaging the lug, a pintle for said cut-off fashioned to provide a pivot pin with an angled portion and terminal extension, a float secured to the terminal extension, off-sets on the cut-off engaging the angled portion of the pivot pin, an adjustable spring for maintaining the cut-off in engagement with the aforesaid lug, the meeting faces of said lug and cut-off

being ground and polished, a transverse re-¹⁰ cession in the cut-off whereby the surface contact is reduced, and attached means for purging the valve body.

In testimony whereof, I have hereunto signed my name at Philadelphia, Pennsyl-¹⁵ vania, this 29th day of December, 1923.

ARTHUR R. EARNSHAW.
